FISHING LURE HEAD

Frank V. Koczorowski, 534 E. Park St.,
Toledo, Ohio 43608

Filed July 29, 1974, Ser. No. 492,772

Term of patent 14 years

Int. Cl. D22—05

U.S. Cl. D22—28

FIG. 2

FIG. 3

FIG. 5

FIG. 4

FIG. 1

FIG. 1 is a view in perspective of a fishing lure head showing my new design;

FIG. 2 is a side view in elevation of the fishing lure head;

FIG. 3 is a top view of the fishing lure head;

FIG. 4 is a front view of the fishing lure head; and

FIG. 5 is a rear view of the fishing lure head.

I claim:

The ornamental design for a fishing lure head, substantially as shown and described.
